UNITED STATES PATENT OFFICE.

PHILIPP PFORR, OF BERLIN, GERMANY, ASSIGNOR TO GENERAL ELECTRIC COMPANY,
A CORPORATION OF NEW YORK.

SYSTEM OF SUSPENSION.

1,035,045.

Specification of Letters Patent.

Patented Aug. 6, 1912.

Application filed March 13, 1907. Serial No. 362,174.

To all whom it may concern:

Be it known that I, PHILIPP PFORR, a subject of the Emperor of Germany, residing at Berlin, Germany, have invented certain new and useful Improvements in Systems of Suspension, of which the following is a specification.

The present invention relates to electric railways and more especially to systems of suspension of overhead conductor wires from which current is collected by a trolley or other collecting device carried by the car propelled by the current collected.

What is known as the catenary system of suspension has been used heretofore to a limited extent, and it consists of one or more stout wires or cables supported above the working wire with considerable sag to each span and from which the working wire is directly suspended by vertical hangers or tie rods disposed at relatively frequent intervals. This form of suspension has certain advantages over the ordinary system of suspension in that it requires fewer points of support, *i. e.*, poles, and the working wire is, by reason of the large number of points of suspension, relieved of much strain so that it is less liable to become broken, and in case it should break, it is impossible for the broken ends to fall sufficiently to become dangerous to persons or things passing along the roadway; moreover the sagging effect of the working wire is somewhat diminished so that for high speed cars and systems of transmission of high tension, there is less arcing between working wire and collector than in ordinary forms of suspension.

The catenary systems of suspension heretofore in use have the disadvantage that the expansion and contraction of the catenary wire or cable under variations in temperature cause the working wire to be raised and lowered more or less at certain points, while at other points it remains substantially stationary and as a consequence it is impossible to maintain parallelism between the working conductor and the car tracks.

The present invention has for its object to provide a system of suspension which shall overcome the above-mentioned disadvantages and also lessen the number of poles used.

Referring to the accompanying drawing forming a part of this specification. Figure

1 shows in side elevation a system of catenary suspension as heretofore constructed; Fig. 2 is a similar view of my improved system of suspension; Fig. 3 is a plan view thereof; Fig. 4 is an elevation transverse to the roadway and showing a double track system; and Fig. 5 is a similar view showing a single track system.

As shown in Figs. 2 to 5, the posts 1 carry near their upper ends braced cross-bars 2, 65 on which are located insulators 3 upon which rest the catenary or messenger cables 4. An intermediate suspension cable 5 extends along beneath each of the cables 4 and is connected thereto at points 6 located equidistant from the insulators 3 at about one-quarter the main span. A lower supporting cable 7 is connected to the intermediate suspension cable 5 at points 8 located equidistant from the points of suspension 6 of 75 the latter. The working conductor 9 is suspended from the lower cable 7 by means of short vertical suspenders 10 arranged equal distances apart and at equal distances from the points 8. The working conductor 9 is 80 held from swaying sidewise by tie wires 11 extending horizontally therefrom to the posts 1 and at the center of the span by stay wires 12 connected to successive posts 1 and drawn toward each other at intermediate 85 points by short wires 13 connected to the working conductor 9.

In Fig. 1 the full lines indicate the positions assumed by the working conductor 9' and catenary cable 4' when properly adjusted, and the broken lines show the positions assumed by the same parts when slightly contracted by low temperature. The working conductor 9' is carried measurably above its intended position at the center of the span, whereas it remains in substantially its original position at points beneath the supports of the catenary cable 4'. 95

The effect of changes of temperature on my improved system of suspension is indicated in dotted lines, Fig. 2. The working conductor 9 is caused to rise and fall a uniform distance at all points so that when once adjusted in parallelism to the car track 14, no amount of expansion or contraction in 100 the supporting system will disturb the parallelism.

Instead of employing three suspension wires 4, 5, and 7, as shown in Fig. 2, a greater or less number might be used ac- 110

cording to the precision with which it may be desired to suspend the working conductor 9.

I do not desire to restrict myself to the particular form or arrangement of parts herein shown and described, since it is apparent that they may be changed and modified without departing from my invention.

What I claim as new and desire to secure 10 by Letters Patent of the United States, is,—

1. The combination with a suspension wire or cable arranged to sag between supports, of a straight suspended wire, and a sagging intermediate wire attached at intervals to 15 the suspension wire and at more frequent intervals to the suspended wire.

2. The combination with a suspension wire or cable arranged to sag between supports, a suspended wire, and means for supporting 20 the suspended wire from the suspension wire and maintain its alinement throughout changes in the degree of sag of the suspension wire comprising an intermediate wire attached at intervals to the sagging sus-

pension wire and having twice as many 25 points of attachment with the suspended wire.

3. An overhead suspension system for electric railway conductor wires, comprising a main supporting wire or cable supported at 30 intervals above the conductor wire and arranged to sag between points of support, a second supporting wire or cable extending beneath the main supporting wire or cable and rigidly connected thereto at points on 35 opposite sides of and remote from the points of suspension of the latter so as to sag between its points of support, and means for suspending the conductor wire from the second supporting wire or cable at points on 40 opposite sides of and remote from the points of suspension of the latter.

In witness whereof, I have hereunto set my hand this 20th day of February, 1907.

PHILIPP PFORR.
